US00D873829S

(12) **United States Design Patent** (10) **Patent No.:** **US D873,829 S**
(45) **Date of Patent:** **** Jan. 28, 2020**

(54) **DISPLAY STAND AND ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/622,812**

(22) Filed: **Oct. 19, 2017**

Related U.S. Application Data

(63) Continuation of application No. 29/572,679, filed on Jul. 29, 2016, now Pat. No. Des. 800,735, which is a continuation of application No. 29/501,842, filed on Sep. 9, 2014, now Pat. No. Des. 762,649, which is a

continuation of application No. 29/501,043, filed on Aug. 29, 2014, now Pat. No. Des. 762,648.

(57) CLAIM

The ornamental design for a display stand and electronic device, as shown and described.

DESCRIPTION

FIG. 1 is a top front perspective view of a display stand and electronic device showing the claimed design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines in the figures show portions of the display stand and electronic device that form no part of the claimed design.
